UNITED STATES PATENT OFFICE.

JOSEPH M. KAYE, OF CHICAGO, ILLINOIS, ASSIGNOR TO EISEMAN, KAYE COMPANY, OF CHICAGO, ILLINOIS, A CORPORATION OF ILLINOIS.

KEYLESS LOCK.

Application filed November 6, 1922. Serial No. 599,317.

To all whom it may concern:

Be it known that I, JOSEPH M. KAYE, a citizen of the United States, residing at Chicago, in the county of Cook and State of Illinois, have invented a new and useful Improvement in Keyless Locks, of which the following is a specification.

My invention relates to an improvement in the class of keyless locks used on hand-bags, brief-cases, toilet cases and boxes, reticules, and the like receptacles. The lock referred to comprises a latch-member to enter an opening in the casing of the companion member, which is provided with a bolt reciprocal relative to the opening when the two members are in operative relation, to enable the latch, when projecting through the hole, to be releasably engaged by the bolt, which is ordinarily spring-pressed to resiliently retain it in its locking position.

The primary object of the present improvement is to prevent the bolt from accidentally releasing the latch; and my invention consists in adjustable means for that purpose.

In the accompanying drawing—

Figure 1 is a face view of the lock provided with my improvement in its preferred form and illustrated in exaggerated dimensions;

Figure 2 is a rear view of the same, but with parts broken away to show details;

Figure 3 is an enlarged section on line 3—3 of either of Figs. 1 or 2;

Figure 4 is an enlarged section on line 4—4 of either of Figs. 2 or 3.

The latch-member 7 is adapted to be secured, as usual, centrally on the outer face of the edge portion of one of the jaws or the closure-flap of a receptacle equipped with a keyless lock of the class referred to. As shown, this member comprises a rectangular plate 8 provided with an edge flange 8^a and containing a longitudinal slot 8^b, at the ends of which those of a pin 9 are removably confined in bearings 9^a on the inner or rear face of the plate; and a latch 10, provided with a hooklike tongue 10^a on its free end-portion, has a sleeve 10^b formed on its opposite end to pivotally surround the pin 9 about a helical spring 11 thereon tending to raise or open the latch. The latch-member may be of any suitable construction, that shown being well-known and in common use.

The bolt-member 12, as represented in the

drawings and also of well-known general construction, is adapted to be secured on a receptacle with which a keyless lock is to be used, in position to cooperate with the latch-member. It comprises a rectangular plate 13, shown to be of larger dimensions than the plate 8 of the latch-member and provided with an edge-flange 13^a and a central keeper-hole 14 to receive the tongue 10^a of the latch 10. In the back of the plate 13 is rigidly secured, as by screws 15 having washers 15^a applied to their inner ends to lie within the confines of the flanged plate 13 or casing, an end-flanged plate 16, through the flanges of which the screws are passed, the plate thus forming a guiding space for housing the bolt 17 to adapt it to be reciprocated relative to the hole 14. The bolt is on a stem 18 passing through a vertical slot 18^b in the plate 13 and the inner end portion of the bolt and terminating as shown in Fig. 2, in an arch-shaped opening 16^a in the housing-plate 16. The stem 18, which is rotatable in its bearing in the bolt for the feature of my improvement in its preferred embodiment, hereinafter described, is secured by a nut 19 and provided on its outer end with a handle of any suitable form, that shown being a knob 20, or button carrying a pivotally suspended loop 20^a. The bolt is spring-pressed by a spring 17^a confined against it to tend to hold it resiliently in its normal position with its advance edge extending part way across the hole 14.

On the inner end of the stem 18 is secured to rotate with it a stop-finger 21, which is preferably in the form of a T to provide arms 21^a (Fig. 2) of slightly springy quality and having depressions formed in their end-portions to produce protuberances 21^b for entering recesses 21^c in the adjacent surface of the bolt, thereby to frictionally retain the finger in either of its two bolt-obstructing and non-obstructing positions.

A receptacle provided with a keyless lock of the kind referred to is locked, when closed, by the latch-tongue 10^a on the one member of the lock projecting through the hole 14 in the other member thereof and being engaged by the bolt 17. For the unlocking purpose, the handle 20 is manipulated to withdraw the bolt from the latch, thereby releasing the latter. However, in this class of lock the bolt is liable to be accidentally withdrawn

and thus unlock the receptacle with the result of opening the latter and leaving it open unconsciously to the person carrying it, in which condition the receptacle may be surreptitiously rifled, or the contents may fall out and be lost. With my improvement in such a lock, accidental opening of the receptacle may be avoided, since after locking, by turning the handle and with it the stem halfway around, the finger 21 will abut against the lower edge of the recess 16^a in the bolt-housing plate 16 and act as a stop against retraction of the bolt from engagement with the latch-tongue 10^a. For there-
after unlocking the receptacle, the handle is turned, preferably another halfway around, to disengage the finger from its stopping position, whereupon the handle may be manipulated to retract the bolt for releasing the latch. In either position of the stop-finger, it will be frictionally held by engagement of the projections 21^b with the recesses 21^c.

I realize that considerable variation is possible in the details of the construction herein shown, and I do not intend to limit myself thereto, except as pointed out in the appended claims, in which it is my intention to claim all the novelty inherent in the device as broadly as is permitted by the state of the art.

I claim:

1. In a keyless lock, in combination with a latch-equipped member, a bolt-containing member comprising a casing provided with

an opening to receive the latch tongue and containing a bolt-housing having an opening in its inner end, a bolt guidingly confined in said housing to be reciprocated relative to said opening, a stem passing rotatably through the casing and bolt and reciprocable with the latter, a handle on the outer end of the stem and a stop-finger on the inner end thereof and rotatable therewith in said housing-opening to engage the base thereof in the locking position of the bolt to obstruct retraction of the bolt from said position.

2. In a keyless lock, in combination with a latch-equipped member, a bolt-containing member comprising a casing provided with an opening to receive the latch tongue and containing a bolt-housing having an opening in its inner end, a bolt guidingly confined in said housing to be reciprocated relative to said opening, a stem passing rotatably through the casing and bolt and reciprocable with the latter, a handle on the outer end of the stem, and a stop-finger on the inner end thereof and rotatable therewith in said housing-opening to engage the base thereof in the locking position of the bolt to obstruct retraction of the bolt from said position, said tongue having arms provided with projections to enter corresponding recesses in the bolt for frictionally retaining the stop-finger in adjusted position.

JOSEPH M. KAYE.
